UNITED STATES PATENT OFFICE.

STEWART B. BARTLEY, OF SHAWNEE, TENNESSEE.

DESIGN FOR AN AGITATOR-STAFF FOR WASHING-MACHINES.

SPECIFICATION forming part of Design No. 31,718, dated October 24, 1899.

Application filed September 21, 1899. Serial No. 731,229. Term of patent 7 years.

To all whom it may concern:

Be it known that I, STEWART B. BARTLEY, a citizen of the United States, residing at Shawnee, in the county of Claiborne and State of Tennessee, have invented and produced a new and original Design for an Agitator-Staff for Washing-Machines, of which the following is a specification.

This invention relates to a new and original design for an agitator-staff for washing-machines; and it has for its object to provide a design of this character that shall be both useful and ornamental.

The leading feature of the design resides in a straight arm provided intermediate its ends with a flat circular enlargement and contiguous to said enlargement with a pair of spaced parallel pin extensions.

The minor features of the design are the flat circular enlargement of the arm having a central square opening and the arm provided with a flat widened portion at the end adjoining the circular enlargement, said flat widened portion of the arm having a pair of oppositely-located upwardly-convergent inclined shoulders meeting the adjacent peripheral edges of the circular enlargement in acute angles.

Additional minor features of the design are the flat widened end portion of the arm being provided with oppositely-located transversely-alined straight shoulders at the bases of the pin extensions and the arm provided with an ovoidal-shaped tip at the end opposite said pin extensions.

In the drawings, Figure 1 is a perspective view of an agitator-staff for washing-machines

embodying the herein-described design. Fig. 2 is a plan view thereof.

Referring to the accompanying drawings, 40 the numeral 1 designates the straight arm of the staff of a flat rectangular form and provided at one end with an ovoidal-shaped tip 2. At a point intermediate its ends the straight arm 1 is provided with a flat circular enlargement 3, having a central squared opening 4 and the opposite convexed lobe portions 5, respectively, projecting beyond the opposite side edges of the arm. At the end adjoining the circular enlargement 3 the arm 4 is provided with a flat widened portion 6, having projected therefrom in the plane of the arm a pair of spaced parallel cylindrical pin extensions 7 of equal length. At the bases of the pin extensions 7 the widened end portion 55 6 of the arm is provided with the oppositely-located transversely-alined straight shoulders 8, and contiguous to the straight shoulders 8 said widened end portion is further provided with the oppositely-located upwardly-convergent inclined shoulders 9, which meet the contiguous peripheral edges of the circular enlargement in acute angles.

What is claimed is—

The design for an agitator-staff for washing-machines, herein shown and described.

In testimony that I claim the foregoing as my own I have hereto affixed my signature in the presence of two witnesses.

STEWART B. BARTLEY.

Witnesses:

A. J. WOLF,
FRED. TONEY.
